SAFETY DEVICE FOR LIFTING MECHANISM

John B. Harrison and Lawrence F. Jaseph,
Memphis, Tenn., assignors to Rotary Lift Com-
pany, Memphis, Tenn., a corporation of Dela-
ware

Application January 13, 1951, Serial No. 205,904

12 Claims. (Cl. 60—52)

1

Our invention relates generally to safety devices for lifting mechanisms, and more particularly to mechanisms of this character for use with hydraulic lifts of the two-post type having movement equalizing means.

It is frequently desirable to provide more than one hydraulic ram in a lifting mechanism for heavy objects, and in such apparatus it is desirable to provide equalizing means to make certain that the several rams will be elevated and lowered at the same rate with the result that the platform or other support carried by the upper ends of the ram plungers will remain level at all times. In such apparatus, it is also highly desirable to provide safety means to prevent lowering of the plungers and the load carried thereby, should the hydraulic pressure operating on the plungers fail. This is particularly true in lifts for heavy devices for the emission of radiant energy in the treatment of pathological conditions, where the heavy apparatus must be suspended over the patient. The invention is therefore disclosed herein as applied to a lifting mechanism for an apparatus of this character.

It is the primary object of the invention to provide an improved safety device and controls for a hydraulic lifting mechanism, which will be operable to sustain the moving part of the lifting mechanism as well as a heavy load carried thereby in the event of a failure or leakage in the hydraulic system.

A further object is to provide an improved pawl and ratchet safety device for lifting mechanisms, together with improved control circuits rendering the latter effective at all times except when the manual controls are operated to lower the load.

A further object is to provide an improved lifting mechanism having an improved safety device and control circuits which are simple in construction, reliable in operation, and which may be economically manufactured.

Other objects will appear from the following description, reference being had to the accompanying drawings, in which:

Fig. 1 is an elevational view of the lifting mechanism;

Fig. 2 is a plan view thereof;

Fig. 3 is an enlarged fragmentary detail, partly sectionalized, showing one of the plungers and the manner of anchoring the equalizing chains;

Fig. 4 is a sectional view taken on the line 4—4 of Fig. 3;

Fig. 5 is a horizontal sectional view taken on the lines 5—5 of Figs. 1 and 3;

2

Fig. 6 is a fragmentary sectional view taken on the line 6—6 of Fig. 1, showing the parts to an enlarged scale;

Fig. 7 is a broken sectional view taken generally along the line 7—7 of Fig. 6;

Fig. 8 is a fragmentary sectional view taken on the line 8—8 of Fig. 1;

Fig. 9 is a fragmentary sectional view taken on the line 9—9 of Fig. 1; and

Fig. 10 is a hydraulic and electrical circuit diagram of the controls for the lifting mechanism.

Referring to Fig. 1, the lifting mechanism comprises a pair of cylinders 10 and 11 suitably secured in the building foundation 12 and secured respectively to the walls 14 and 15, by means including brackets 13. Plungers 16 and 17 are respectively reciprocable in the cylinders 10 and 11, being supplied with hydraulic operating fluid under pressure in a hereinafter to be described manner, through conduits 18 and 19 connected to suitable control valves, and a source of hydraulic fluid.

A box-section load supporting beam 20 is fabricated from suitable channels 21 and plates 22, as best shown in Fig. 8, the parts being welded together to form a unitary structure. The ends of this beam are suitably secured to the upper ends of the rams or plungers 16 and 17, respectively, as best illustrated in Figs. 6 and 7. Each of the plungers is guided for rectilinear movement by a pair of rails 24, 25, which are welded or otherwise secured to vertical channels 26 and 27, respectively, and the latter are secured to the walls 14 and 15 by a plurality of brackets 28.

Each of the rams and its guides and supporting structure are partly enclosed by a suitable sheet metal housing 30. The channels 26, 27 have a chain anchor bar 32 rigidly secured thereto, as by welding, and their upper ends support a cap plate 36 provided with suitable reinforcing plates 38, 39 and 40, the plate 40 being suitably secured to the wall 15. The cap plate 36 of the right hand plunger guide structure forms a support for the end of a chain A, the end of the latter being secured to a stud 42 provided with an adjusting nut 44, while the cap plate 36 of the left hand plunger guide structure serves similarly as a support for the anchoring adjustable stud 46 secured to a chain B, the other end of chain B being secured to the anchoring bar 32 of the right hand plunger guiding structure. In a similar manner the other end of chain A is anchored to an anchoring bar 33 of the guide structure for the left hand plunger.

As best shown in Figs. 6 and 7 the beam chan-

hels 21 have collars 48 and 49 secured thereto for the reception of a fixed shaft 50 having shoes 52 and 53 pivoted at the ends thereof, the shoes engaging guide rails 24 and 25 respectively. The shaft 50 for the right hand plunger has a pair of sprocket wheels 56, 57 secured thereto for engagement with chains A and B, respectively. These sprocket wheels are rigidly secured together and to ratchet wheels 58 and 59 by a plurality of studs 60, the sprocket wheels being suitably spaced by a ring 62 and thus firmly clamped to the ratchet wheels 58 and 59. The ratchet wheels 58 and 59 are provided with counterbores for the reception of bearing bushings 64 for engagement with the fixed shaft 50.

A two-toothed pawl 66, engageable with the ratchet wheel 58, is pivoted on a stub shaft 68 which is suitably secured in a pair of bracket plates 70 which are in turn secured to a beam end plate 72 and a reinforcing and mounting plate 74. A pawl 76, similar to the pawl 66, is similarly mounted for engagement with the ratchet wheel 59. The pawl 66 is adapted to be disengaged from the ratchet wheel 58 by a solenoid 78, the upward stroke of the pawl being limited by an adjustable locked screw 80. The plates 74 serve as a support for a normally open switch 82 preferably having a roller arm 84 for engagement with the pawl 66, the switch being adapted to be closed when the pawl 66 is fully disengaged from the ratchet wheel 58. Similarly, the pawl 67 is provided with an actuating solenoid 79 (not shown in Figs. 6 and 7) and is adapted to close a switch 83, in the same manner that switch 82 is operated. Since the latter parts are identical with the corresponding parts previously described, they are indicated by reference characters enclosed in parentheses in Fig. 7 in order to avoid unnecessary complications in the drawings.

Each of the pawls 66, 67 has a pair of spaced teeth 85 so that the load on the pawls and ratchet wheels will be distributed between two teeth. The ratchet wheels 58 and 59 have their teeth out of alignment to the extent of one-half the tooth pitch, to reduce lost motion.

At the upper end of the left hand plunger there is a sprocket and bearing construction similar to that shown in Figs. 6 and 7 except that the ratchet wheels 58, 59, pawls 66 and 67, solenoids 78, 79, and switches 82, 83, together with their mountings, are omitted. These parts could be included except for the advantageous reduction in cost resulting from their omission. The manner in which the chains A and B pass around the sprockets at the upper ends of the plungers is indicated in Fig. 1, it being understood that these chains operate in more or less conventional manner to assure that the plungers 16 and 17 are raised and lowered at the same rate, and thus that the beam 20 is maintained horizontal at all times.

The load which is raised and lowered by the lifting mechanism is illustrated as comprising a radiation emitting apparatus 90 which is supported, as best indicated in Fig. 8, by a pair of angle shaped saddles 92, 93 which are welded together and rest upon shim plates 94 and 95 which in turn rest upon the top plate 22 of the beam section. Tension bars 96 and 97, together with housing plates 98, are secured to the saddle angles 92, 93 by studs 100. Keys 102 and 103 fitting closely in suitable complementary grooves formed in the tension bars and the saddle angles, provide an additional weight bearing

connection between the saddle 92, 93 and the load supporting tension bars 96 and 97. A sheet metal duct 106 is suitably secured to the beam plate 22 of the beam to cover conductors leading to the radiation emitting apparatus 90.

In the event that remote indication of the degree of elevation of the apparatus 90 is required, a self-synchronous three phase generator with single phase excitation may be mounted within a suitable housing 108 and geared, through a speed increasing gearing, to the adjacent sprockets over which the chains A and B pass, and the output of this generator supplied to a remote self-synchronous receiver, which operates in synchronism with the generator, and is geared to a suitable indicator.

Suitable hydraulic and electric controls are provided for the operation of the lifting mechanism, these including, as best shown in Fig. 9, a down limit switch LSD, an upward travel limit switch LSU, and a safety limit switch LSS mounted upon channel 27. These switches are adapted to be operated by a cam 110 which is suitably secured to the beam 20. These three limit switches are of conventional construction, having roller bearing arms 112 which, when engaged by the cam 110, are swung counterclockwise to open their contacts. In other words, these are normally closed contacts.

These limit switches are connected in a control circuit as diagrammatically illustrated in Fig. 10. Main current supply conductors L1, L2, and L3 are adapted to be connected to a power line by closing a main switch 116. A motor 118 is adapted to be connected to these power lines upon closure of contacts U1, U2, and U3. A pair of overload relay heaters OL are connected respectively between the contacts U1 and U2, and the motor 118. The motor 118 drives a pump 120 which draws oil or other suitable hydraulic actuating fluid from a reservoir 122 and delivers it to a discharge pipe 124, the pressure in the latter being prevented from exceeding a predetermined maximum value by a spring loaded pressure relief valve 126. A check valve 128 is connected between conduit 124 and conduit 130 to prevent reverse flow from the lift cylinders 10 and 11, the conduit 130 being connected to these cylinders by the conduits 18 and 19.

Thus, when the motor 118 is energized, hydraulic fluid under pressure is supplied to the cylinders 10 and 11 to force the plungers 16 and 17 thereof upwardly. When the plungers are to be lowered at normal speed, a solenoid 132 is energized to open a valve 134 which permits oil to flow from the cylinders to the reservoir 122 at a rate which may, if desired, be controlled by a restriction 136. When the lift is to be lowered slowly, a solenoid 138 is energized to open a valve 140 which permits flow from the plunger cylinders through a restriction 142 to the reservoir 122. The restriction 142 may be fixed or variable, depending upon the character of operation desired.

It is believed that the electrical control circuits may best be described in conjunction with a description of the operation of the various parts through a complete cycle.

Assuming that the lift is in lowered position and that it is desired to raise it, an Up push button is operated to close contacts 141 and thereby complete a circuit through a relay coil UA which is in series with normally closed contacts D1, S1, LSU, and LSS across the lines L1 and L3. Energization of relay UA causes

closure of its normally open contacts **UA1** and thereby completes a circuit from **L1** through push button contact **141**, contact **UA1**, a relay coil **U**, the contacts **OL1** of the overload relay, and the contacts **LSS** of the safety limit switch, to the line **L3**. Energization of relay **U** results in closure of the contacts **U1**, **U2**, and **U3**, thereby energizing motor **118**, causing the pump to supply hydraulic fluid under pressure past the check valve **128** to the plunger cylinders **10** and **11**, thus raising the plungers at a rate determined by the capacity of the pump **120**.

If it is desired to arrest the upward movement at any time, it is necessary merely to release the push button **141**, which, through deenergization of relay **U**, cuts off supply of current to the motor **118**. The check valve **128** will normally maintain the plungers in the elevated position, but if, due to any slight leakage in the system, there is a tendency for the plungers to drift downwardly, one of the pawls **66**, **67** will, after downward movement of but a short distance, engage the teeth of its ratchet wheel **58** or **59**, and thereby stop further downward movement. Since the teeth of the ratchet wheels are spaced apart by one-half a tooth, the maximum distance that the lift may descend under these conditions is very small. If the operator maintains the Up push button contacts **141** closed, limit switch **LSU** will open as the lift reaches the normal upper limit of its travel, and thus, through deenergization of relay **UA**, will open contacts **UA1** and thereby deenergize relay **U** and stop the motor **120**. If for some unforeseen reason the limit switch **LSU**, or any other part of the related circuit elements, fails to operate and the lift moves beyond its normal upward limit of travel, the cam **110** will operate the safety limit switch **LSS** to open its contacts, thus deenergizing all of the control circuits and necessarily stopping the operation of the motor **118**.

Assuming that the lift has now been raised and it is desired to lower it, the operator will depress the Down push button, thereby closing switch **146** and completing a circuit through the down valve solenoid **132**, which circuit may be traced as follows: From **L1**, push button contacts **146**, solenoid **132**, conductor **147**, switches **82** and **83**, down limit switch **LSD**, contacts **UA2**, conductor **148**, limit switch **LSS**, to line **L3**. Switches **82** and **83**, it will be recalled, are closed only when the pawls **66** and **67**, respectively, are in their elevated positions due to energization of the solenoids **78** and **79**, respectively. These solenoids are energized in the following manner: Upon closure of the Down push button contact **146**, current is supplied to relay **D** through a circuit from the conductor **L1**, through the push button switch **146**, coil **D**, down limit switch **LSD**, contacts **UA2**, conductor **148**, and the normally closed safety limit switch contact **LSS** to line **L3**. If there has been any slight downward drift of the lift, the pawl **66** or **67** will have engaged the teeth of its associated ratchet wheel **58** or **59**, and will be sustaining the load. Either the solenoid **78** or solenoid **79** cannot, therefore, disengage the pawl from its ratchet wheel, and as a result, switch **82** or **83** will be open, and therefore under these circumstances the previously described circuit through the down valve operating solenoid **132** cannot be completed. (It will be understood that normally only one of pawls **66**, **67** will thus be prevented from being swung upwardly by its solenoid.) However, a circuit will be completed from line **L1** through push button contact **146**, contact

D3, which will then be closed, normally closed contacts **P1**, relay coil **U**, overload contacts **OL1**, conductor **148**, safety limit switch **LSS**, to **L3**. Energization of relay **U** will cause the motor **118** to start and commence forcing the plungers **16** and **17** upwardly. This will continue until the strain on the pawl **66** or **67** is released, whereupon its associated solenoid **78** or **79** will pull the pawl upwardly and close switches **82** or **83**. When this occurs, relay coil **P** is energized through a circuit traced as follows: From **L1**, push button contacts **146**, closed contacts **D3**, conductor **150**, relay coil **P**, switches **82** and **83**, down limit switch **LSD**, contacts **UA2**, conductor **148**, safety limit switch **LSS**, to **L3**. When the coil **P** is energized, contacts **P1** open, thus deenergizing relay coil **U** and stopping the motor. At the same time the current may now flow through solenoid **132** through the previously described circuit, since switches **82** and **83** are now closed.

When it is desired to adjust the position of the lift by permitting it to descend slowly, the Slow push button contacts **152** are closed to energize relay coil **S** through a circuit traced as follows: From **L1**, push button contacts **152**, coil **S**, down limit switch **LSD**, contacts **UA2**, safety limit switch **LSS**, to line **L3**. Closure of contacts **S2** results in energization of coils **78** and **79**, thereby closing switches **82** and **83**, and completing a circuit to energize solenoid **138** which is traced as follows: From **L1**, push button contacts **152**, conductor **154**, "slow" valve operating solenoid **138**, conductor **147**, switches **82** and **83**, limit switch **LSD**, contacts **UA2**, conductor **148**, safety limit switch **LSS**, to line **L3**. This again assumes that neither of the pawls **66**, **67** is locked in engagement with its associated ratchet wheel, and that their associated solenoids **78** or **79** may swing the pawls to their upper positions, closing switches **82** and **83**.

However, if either pawl **66** or **67** is in weight bearing engagement with its ratchet wheel, one of the switches **82**, **83** may be open, and under these circumstances the energization of relay coil **S** results in the closure of contacts **S3** and energization of relay coil **U**. Energization of relay coil **U** in the manner previously described will result in energization of the motor **118** to raise the lift sufficiently to relieve either of the pawls **66** or **67** of its weight carrying engagement with its associated ratchet wheel. As soon as this occurs, both of the solenoids **78** and **79** will be capable of closing switches **82** and **83**, and this will permit energization of relay coil **P** through a circuit traced as follows: From **L1**, through Slow push button contacts **152**, now closed, contacts **S3**, relay coil **P**, closed switches **82** and **83**, closed limit switch **LSD**, closed contacts **UA2**, conductor **148**, and safety limit switch **LSS**, to line **L3**. Energization of relay coil **P** will result in opening its contacts **P1** and thereby break the circuit supplying current to relay coil **U**, with the result that the motor **118** will again be deenergized and the lift may descend at a rate determined by the size of the restriction **142**. This may occur because valve **140** will then be opened by its solenoid **138**, the latter being energized through a circuit which may be briefly traced as follows: From **L1**, push button contactor **152**, conductor **154**, solenoid **138**, conductor **147**, closed switches **82**, **83** **LSD**, and **UA2**, conductor **148**, and safety limit switch **LSS**, to line **L3**.

From the foregoing, it will appear that the pawls **66** and **67** are in condition for engagement with their ratchet wheels **58** and **59**, respective-

ly, at all times, except when either the Down push button or the Slow push button is depressed. Since, in the particular apparatus disclosed herein, the radiation emitting apparatus 90 is utilized for the treatment of a patient lying beneath it, and since this radiation emitting apparatus may weigh in the order of 18 tons, it will be appreciated that the provision of adequate safety means to prevent undesired lowering of the lift is of extreme importance.

It will be clear that when the beam reaches the lower limit of its stroke, limit switch LSD is opened, thus opening both possible circuits through the valve controlling relays 132 and 138. Likewise, when the Up push button is depressed, the relay coil UA is energized, and contacts UA2 are opened so that accidental simultaneous depression of either the down push button contactors 146 or the slow push button contactors 152 cannot have any effect.

While we have shown and described a preferred embodiment of our invention, it will be apparent that numerous variations and modifications thereof may be made without departing from the underlying principles of the invention. We therefore desire, by the following claims, to include within the scope of the invention all such variations and modifications by which substantially the results of our invention may be obtained through the use of substantially the same or equivalent means.

We claim:

1. A hydraulically operated lift comprising a pair of spaced parallel cylinders; plungers reciprocable in said cylinders; a beam connected to the upper ends of the plungers; a pair of sprockets secured together and mounted for rotation at each end of the beam; a pair of chains to insure translatory movement of the beam, each chain having one end anchored above one end of the beam, meshing with one of each pair of sprockets, and having its other end anchored below the other end of the beam; a ratchet wheel rigidly connected to one of the pairs of sprockets; a pawl cooperable with the ratchet wheel to prevent rotation thereof in the direction it rotates as the beam is lowered; a solenoid which when energized tends to disengage the pawl; and remote switch and circuit means for controlling the energization of the solenoid.

2. The combination set forth in claim 1, in which there is an electromagnetically operated valve to control the discharge of hydraulic fluid from the cylinders, and in which the remote switch means controls the energization of both the solenoid and the electromagnetically operated valve.

3. The combination set forth in claim 2, in which is included an electric motor, a pump driven thereby, conduits connecting the pump outlet to the cylinders, a switch closed by the pawl when it is moved out of engagement with the ratchet means, and in which the last named switch is connected in the remote switch, and circuit means to prevent energization of the solenoid and electromagnetically operated valve when the pawl is in engagement with its ratchet wheel.

4. The combination set forth in claim 3, in which the remote switch and circuit means includes a relay for energizing the motor when the pawl operated switch is open.

5. In a hydraulic lift mechanism having a cylinder, a plunger reciprocable in the cylinder, load supporting structure carried by the plunger; the combination of a pawl and ratchet mechanism

operable to prevent lowering of structure; an electric motor; a pump driven thereby to supply hydraulic fluid under pressure to the cylinder; an electromagnetically operated valve to control the discharge of hydraulic fluid from the cylinder; a manually operable switch and an electric circuit to control the supply of current to the electromagnetically operated valve; and a second switch operable by the pawl and ratchet mechanism to prevent completion of said circuit whenever the pawl is engaged with the ratchet.

6. In a two-post lift mechanism, the combination of a pair of cylinders each having a plunger reciprocable therein, a load carrying beam connecting the upper ends of said plungers, a pair of rigidly connected sprocket wheels mounted for rotation at the upper end of each of the plungers, a pair of chains each having one end anchored above the upper limit of travel of one of the plungers and its other end anchored below the lower limit of travel of the other plunger, said chains being enmeshed with said sprockets in a manner to cause equalization of the rate of the upward and downward travel of the plungers, a pair of ratchet wheels rigidly secured to one of the pairs of sprockets, pawls respectively engageable with the ratchet wheels in a manner to prevent rotation of the sprocket wheels in the direction in which they rotate upon the downward movement of the plungers, a solenoid for disengaging the pawls, a pair of switches respectively operated by the pawls when they have been released from engagement with their ratchet wheels, a manually operable switch, and means comprising a circuit including said pawl operated switches in series to cause hydraulic power fluid to be supplied to the cylinders upon operation of the manually operable switch whenever said pawl operated switches are open and to effect discontinuance of the supply of the hydraulic power fluid to the cylinders after said pawl has been freed from engagement with its ratchet wheel by its solenoid and has effected closure of both of said pawl operated switches.

7. In a two-post lift mechanism, the combination of a pair of spaced cylinders each having a plunger reciprocable therein, a beam connecting the upper ends of said plungers, a pair of rigidly connected sprocket wheels mounted for rotation at the upper end of each of the plungers, a pair of chains each having one end anchored above the upper limit of travel of one of the plungers and its other end anchored below the lower limit of travel of the other plunger, said chains being enmeshed with said sprockets in a manner to cause equalization of the rate of the upward and downward travel of the plungers, a ratchet wheel rigidly secured to one of the pairs of sprockets, a pawl engageable with the ratchet wheel in a manner to prevent rotation of the sprocket wheels in the direction in which they rotate upon the downward movement of the plungers, a solenoid for disengaging the pawl, a switch closed by the pawl when it is moved from engagement with the ratchet wheel by the operation of the solenoid, a source of a hydraulic fluid under pressure, and a control circuit including said switch to cause hydraulic power fluid from said source to be supplied to the cylinders upon manual operation of a contactor in the control circuit whenever said pawl operated switch is open and to effect discontinuance of the supply of the hydraulic power fluid to the cylinders after said pawl has been freed

from engagement with its ratchet wheel by its solenoid and has effected closure of said switch.

8. In a lift structure, a cylinder; a plunger reciprocable in the cylinder; a latch normally operating to prevent downward movement of the plunger; a solenoid connected to the latch to release the latter when the solenoid is energized; a switch operated by the latch when it is moved to releasing position by the solenoid; a source of hydraulic fluid; an electric motor and pump driven thereby connected to supply hydraulic fluid from the source to the cylinder; an "Up" switch manually operable to energize said motor; a "Down" switch; a valve controlling the discharge of hydraulic fluid from the cylinders; electromagnetic means for operating said valve; a circuit including said "Down" switch, said electromagnetic means, said latch operated switch, and the source of electrical energy, to effect opening said valve whenever said latch operated switch and said "Down" switch are closed at the same time; and an additional circuit including said "Down" switch for causing energization of said motor until said latch has operated its associated switch.

9. In a lift structure, a cylinder, a plunger reciprocable in the cylinder, a latch normally operating to prevent downward movement of the plunger, a solenoid connected to the latch to move the latter to unlatched position when the solenoid is energized, a first switch closed by the latch when it is moved to unlatched position by the solenoid, a source of hydraulic fluid, an electric motor and pump driven thereby connected to supply hydraulic fluid from the source to the cylinder, a second switch manually operable to energize said motor, a third switch, a valve controlling the discharge of hydraulic fluid from the cylinders, electromagnetic means for operating said valve, a circuit including said third switch, said electromagnetic means, said second switch, and the source of electrical energy, to effect opening said valve whenever said latch operated switch and the third switch are closed at the same time, and an additional circuit including and controlled by said third switch for energizing said motor until said second switch is opened by the disengagement of the latch.

10. In a lift mechanism comprising a cylinder and plunger reciprocable therein, the combination of a latching mechanism normally operable to hold said plunger against downward move-

ment, a releasing solenoid connected to the latching mechanism, a motor and pump driven thereby to supply hydraulic fluid under pressure to said cylinder, an electromagnetically operated valve controlling the discharge of hydraulic fluid from the cylinder, manually operable switch and circuit means to effect energization of said electromagnetically operated valve to open the latter and to energize said solenoid, means in said circuit means to prevent energization of said electromagnetically operated valve upon operation of said switch whenever the latching mechanism is effective and to cause energization of the motor until the latching means is released and thereupon to discontinue energization of said motor.

11. In an elevator having a load support and means for raising and lowering it, the combination of means for insuring translatory movement of the load support, said means including a part which must rotate in a certain direction as the load support moves downwardly, a pawl and ratchet mechanism connected to said part to prevent downward movement of the load support when the pawl is in engagement with the ratchet, control means operable to effect lowering of the load support, and means controlled by the pawl and ratchet mechanism to cause initial elevation of the load support sufficient to release the pawl from its ratchet and thereafter to effect lowering of the load support.

12. In an elevator having a load support and means for raising and lowering it, the combination of means for insuring translatory movement of the load support, said means including a part which must rotate in a certain direction as the load support moves downwardly, a ratchet wheel rigidly secured to said part, a pawl cooperable with the ratchet wheel to prevent rotation of said part in said certain direction, control means operable to a position to cause lowering of the load, control means to move the pawl from ratchet engaging position, means operable by the control means to cause initial upward movement of the load support, and means operated by the pawl upon movement to a position in which it is free from the ratchet wheel to render said control means effective to lower the load support.

JOHN B. HARRISON.
